GUIDE STRUCTURE FOR FLUSHING VALVE MECHANISM

Clarence J. Davies, Mount Clemens, Mich., assignor to
Lloyd N. McGrath and John G. Tomlan, doing business
as D. & S. Stamping Co., Utica, Mich., co-partners

Application September 4, 1957, Serial No. 681,996

11 Claims. (Cl. 4—57)

This invention relates generally to water discharge or flushing valve mechanism for toilet flush tanks, and refers more particularly to a structure that may be applied either as an attachment to or part of the original installation to guide the usual vertically movable water discharge bulb or ball valve and its upright stem during operation thereof, so that said valve and stem will function properly at all times without being held or restrained or otherwise restricted in any position thereof.

One of the essential objects of the invention is to provide a guide structure that will positively guide the water discharge bulb or ball valve to and from its seat, and that will permit such valve to move freely in a vertical path relative to said seat, whereby the proper seating of the valve is always insured whenever it is operated.

Another object is to provide a guide structure that will positively guide the upright stem of the bulb or ball valve during vertical movement thereof and that will permit such stem to move freely in a vertical path with the valve, whereby perfect co-ordination of movement of the stem and valve will always be obtained during operation thereof.

Another object is to provide a guide structure wherein the guide means for the stem comprises means for guiding the loop or eye of the usual lifter wire, so that such loop will always be substantially concentric with said stem and will always be in proper vertical alignment or registration with the conventional vertically extending valve stem guide opening in the usual horizontal arm or bracket attached to the overflow pipe in the flush tank, and thus cannot push or bind against said stem or otherwise prevent the bulb or ball valve from dropping properly to closed position on its seat.

Another object is to provide a guide structure wherein the upward movement of the valve stem is limited by a positive stop element, so that the bulb or ball valve will not be raised higher than necessary, and the stop usually built into the fulcrum for the lifter lever may be eliminated entirely.

Another object is to provide a guide structure composed of parts that may be shipped disassembled in an envelope or relatively small package and that can be easily and quickly assembled and installed by the user without requiring special tools.

Another object is to provide a guide structure that can be employed with standard or conventional valve mechanism for toilet flush tanks without substituting or otherwise changing any of the parts thereof.

Another object is to provide a guide structure that is simple in construction, economical to manufacture, efficient in use, and that will insure continuous trouble-free operation of the flushing valve mechanism for toilet flush tanks.

Other objects, advantages and novel details of construction of this invention will be made more apparent as this description proceeds, especially when considered in connection with the accompanying drawings wherein:

2

Figure 1 is a fragmentary front elevation of a flush tank, with parts broken away and showing a guide structure embodying my invention.

Figure 2 is a fragmentary plan view of the operating handle and associated parts, and showing a portion of the front wall of the tank broken away and in section.

Figure 3 is a horizontal sectional view taken substantially on the line 3—3 of Figure 1.

Figure 4 is an enlarged horizontal sectional view taken substantially on the line 4—4 of Figure 1.

Figure 5 is an elevational view of the guide structure illustrated in Figure 1.

Figure 6 is an enlarged fragmentary elevational view of the guide structure illustrated in Figure 5, and showing the crimped connection between the guide wire holder and one of the wires of the guide structure.

Figure 7 is an enlarged fragmentary elevational view of the guide structure illustrated in Figure 5, but showing a wire retainer ring that is employed with the guide wire holder and guide wires, instead of the crimped construction illustrated in Figure 6.

Figure 8 is a cross-sectional view taken substantially on the line 8—8 of Figure 7.

Figure 9 is a view similar to Figure 1, but showing a slight modification.

Figure 10 is a horizontal sectional view taken substantially on the line 10—10 of Figure 9.

Figure 11 is a vertical sectional view taken substantially on the line 11—11 of Figure 10.

Figure 12 is on a vertical sectional view taken substantially on the line 12—12 of Figure 10.

In the drawings, A is a toilet flush tank adapted to receive water in the usual manner from a conventional upstanding water inlet pipe (not shown) under the control of a conventional float carrying arm or lever (not shown). The water inlet valve mechanism and associated elements form no part of the present invention and may be any suitable construction.

B is the usual water outlet fitting extending through the bottom 10 of the tank and having both a seat 11 for the usual vertically movable water discharge bulb or ball valve 12, and a passage 13 to which the usual upstanding water overflow pipe 14 is connected.

15 is the usual upright stem detachably secured to said valve 12 and having a loop or eye 16 at its upper end, and C is the usual bracket clamped upon the upright overflow pipe 14 and having a horizontal arm 17 provided at its free end with a vertically extending tubular portion or opening 18 that receives and forms a guide-way for the stem 15.

D is the usual substantially horizontal lifter lever having the usual longitudinally spaced holes 19 therein adjacent one end thereof, and having its other end bent at substantially right angles thereto as at 19a, and mounted to turn in a fulcrum or sleeve 19b within the upright front wall 20 of the tank. E is the usual lifter wire or link having a vertically extending arm portion 21 provided at its upper end with a hook 22 engaging one of the holes 19 in the lifter lever D and having a horizontal arm portion 23 provided at its outer end with a vertically opening horizontal loop or eye 24, encircling or loosely sleeved on the stem 15, and substantially concentric therewith. F is the usual operating handle having the usual horizontal operating shaft (not shown) rotatably mounted in the fulcrum or sleeve 19b and operatively connected to the bent end portion 19a of the lifter lever D.

60 Preferably, the guide structure G embodying my invention comprises four guide wires 30, a guide wire holder 31, a stop disc or washer 32, and a wire retainer ring 33.

65

As shown, the lower upright portions 34 of the guide wires are spaced laterally apart in the arc of a circle to form a tubular enclosure for guiding the vertically movable ball valve 12 throughout its vertical movement, while the upper upright portions 35 of said wires are spaced closer together in the arc of a circle to form a smaller tubular enclosure for guiding the loop 24 sleeved upon the vertically movable stem 15.

Preferably, the lower ends of the lower portions 34 of the wires are cut on an angle, as at 36, to enable such cut ends to be embedded readily in the usual rubber gasket or washer 37 on the bottom 10 of the tank, so that such lower wire portions 34 will be effectively held against the periphery of the usual circular flange 38 of the water outlet fittings B. If for any reason the gasket 37 should be smaller in diameter, for example, substantially equal in diameter to the flange 38, then the cut lower ends of lower wire portions 34 may rest upon the bottom 10 of the tank.

Located between the lower and upper wire portions 34 and 35 are horizontal wire portions 39 that are terminally connected to the upper ends of the lower wire portions 34 and to the lower ends of the upper wire portions 35. The holder 31 is located at the juncture of the upper wire portions 35 and the horizontal wire portions 39, and effectively retains all of the wire portions aforesaid in proper spaced relation to each other. Preferably, this holder 31 has two vertically spaced horizontally disposed disc portions or plates 40 and 41 respectively, provided centrally thereof with oppositely struck-out tubular portions 42 and 43 that fit one within the other between the discs 40 and 41 and are rigidly secured together. These discs 40 and 41 are provided with vertically aligned holes that receive the upper wire portions 35. The lower disc 40 has a depending peripheral or marginal flange 45 provided with circumferentially spaced notches or recesses 46 that receive the horizontal wire portions 39, while the upper disc 41 has a substantially frusto-conical depressed portion 41a receiving the lower end of the vertically extending tubular portion 18 of the arm 17.

When the parts are manufactured and assembled at the factory, the opposite edges of said recesses 46 are pinched or crimped against opposite sides of the horizontal wires 39, as at 47, to securely retain the parts in assembled relation and thereby prevent any accidental displacement of the wires 30 relative to the holder 31, or of the holder 31 relative to the wires 30. However, when the parts are to be shipped disassembled in an envelope or relatively small package and are to be assembled and installed by the user without requiring special tools, the split spring wire retainer ring 33 is employed by the user when the guide structure is assembled by him prior to installation, and is placed by the user on top of the upper disc 41 so that it engages suitable pre-formed notches 48 in the outer sides of the upper wire portions 35. Thus, in this instance, the ring 33 will be employed instead of the crimped portions 47 to retain the parts in assembled relation and thereby prevent the guide wires 30 from being accidentally displaced from the holder 31 after being assembled therewith prior to installation. Such ring 33 also effectively prevents any accidental displacement of the holder 31 relative to the horizontal wire portions 39 after the assembly is made prior to installation.

The stop disc or washer 32 fits between and preferably engages suitably pre-formed notches 50 in the inner sides of the upper wire portions 35 adjacent their upper ends, so as to be in the upward path of the eye 16 of the stem 15 and thereby limit its upward movement. The ball valve 12 is connected to the stem, consequently such stop disc 32 will also limit the upward movement of the ball valve 12. The spring tension of the upper wire portions 35, which have a tendency to converge at their upper ends before the stop disc 32 is inserted, assists in maintaining the stop disc 32 in assembled relation with the wires. Thus, the ball valve 12 will not be raised

higher than necessary, and the stop usually built into the fulcrum for the lifter lever D may be eliminated entirely.

In use, when the handle F is operated to flush the toilet, the lifter lever D and lifter wire or link E will raise the stem 15 and ball valve 12 so that the latter will be lifted from its seat 11. Water in the tank A may then flow downwardly through the outlet fitting B in the usual manner. When the operating handle F is released, the stem 15, lifter wire E and lifter lever D will then fall or move downwardly, and thereby will reset the operating handle F for future operation. Temporarily, the ball valve 12 will float until the water is substantially drained from the tank A, whereupon the suction created in the outlet fitting B will cause the ball valve 12 to fall onto its seat 11. Between the time when the lifter wire E returns to the lowered reset position just mentioned and the time when the ball valve 12 thereafter falls, as aforesaid, it is essential that the loop 24 of the lifter wire E be held concentric with stem 15 and in proper alignment or registration with the vertically extending tubular portion or opening 18, so that no binding of the stem 15 occurs. My guide structure effectively prevents such binding action.

When the lifter lever D and lifter wire or link E are actuated, as aforesaid, by the operating handle F, the loop 24 of the lifter wire or link E will travel upwardly against the loop or eye 16 of the stem 15 and will cause the latter, and the ball valve 12 connected thereto, to move upwardly. When the loop 24 of the lifter wire or link E moves upwardly, it is guided by the upper portions 35 of the wires 30, and likewise such loop 24 will be guided by said wire portions 35 when it moves downwardly as the ball valve 12 descends toward its seat 11. Since the loop 24 is substantially concentric with the stem 15 and is guided during vertical movement upwardly and downwardly by the upper portions 35 of the wires, it will be apparent that such loop 24 will always be in vertical alignment or registration with the vertically extending tubular portion or valve stem guide opening 18, and thus cannot push or bind against the stem 15 or otherwise restrain said stem or prevent the ball valve 12 connected to said stem from falling properly to closed position on its seat 11.

When the lifter lever D and lifter link E are actuated by the operating handle F to raise the ball valve 12, as aforesaid, the upward movement of said ball valve 12 is limited by the engagement of the eye 16 of the stem 15 with the stop element 32, so that the ball valve 12 will not be raised higher than necessary.

When the ball valve 12 moves upwardly and downwardly, as aforesaid, it is effectively guided by the lower portions 34 of the wires 30, hence the ball valve 12 will always be properly guided from and to its seat 11, and the proper seating of said valve is always insured whenever it is operated.

The guide structure just described is adapted to be applied as an attachment to or incorporated in the water discharge flushing valve mechanism after it has been manufactured or originally installed. However, it is apparent that such guide structure could be applied to or incorporated in said valve mechanism at the time it is manufactured at the factory, if desired.

In Figures 9 to 12 inclusive, I have illustrated a slight modification wherein the guide structure G' includes a cast metal bracket 60 and separate lower and upper upright guide wires 61 and 62, respectively.

As shown, the bracket or casting 60 serves as a wire holder and is clamped upon the upright overflow pipe 14. Preferably, this bracket or casting 60 has a horizontal arm 63 provided at its free end with a spider portion 64 having a central body portion 65 and four radially extending arm portions 66.

The body portion 65 has a vertically extending opening 67 that receives and guides the stem 15, and is provided in the arc of a circle with spaced sockets 68 that receive

the lower ends of the upper guide wires 62 for the loop 24 of the lifter wire or link E. The arm portions 66 of the spider portion 64 are provided at their outer ends in the arc of a circle with suitable sockets 69 that receive the upper ends of the lower guide wires 61 for the bulb or ball valve 12.

The guide wires 61 and 62 respectively comprise separate straight lengths of wire and may be retained in the respective sockets 68 and 69 by any suitable means. For example, such wires may be soldered or may have a press fit in the sockets 68 and 69, or may be embedded in the casting 60 when it is formed. Preferably, the lower guide wires 61 terminate short of the outlet fitting B but extend downward far enough from the casting 60 to effectively guide the bulb or ball valve 12 to and from its seat 11 during upward and downward vertical movement thereof. Thus, the lower ends of these lower guide wires 61 are free to be adjusted relative to each other to provide the proper clearance desired for the bulb or ball valve 12.

The modification just described is adapted to be applied to or incorporated in the original installation of the water discharge flushing valve mechanism at the time it is manufactured at the factory. However, it is apparent that the usual bracket C may be eliminated and replaced by the bracket 60, so that the modified guide structure could be applied as an attachment to or incorporated in the water discharge flushing valve mechanism after it has been manufactured or originally installed.

The function and operation of the modified guide structure G' is the same as the function and operation of the guide structure G, hence it will be unnecessary to describe the use or operation thereof.

What I claim as my invention is:

1. The combination with a toilet tank, a water outlet fitting extending upwardly through the bottom of said tank and having an upwardly opening valve seat, a gasket on the bottom of said tank and surrounding said fitting, an upstanding water overflow pipe connected to said fitting, a vertically movable ball valve engageable with said seat and having an upright stem provided at its upper end with an eye, a bracket mounted upon said overflow pipe and having a horizontal arm provided with a vertically extending tubular portion receiving and forming a guideway for said stem, and actuating means for said ball valve including a pivotally mounted lifter lever, and a lifter link suspended from said lever and having a loop sleeved on said stem below said eye, of a guide structure for said ball valve and said stem operable to preclude any binding action between the loop and stem and between the stem and tubular guideway, comprising a series of wires having intermediate their ends spaced horizontal portions, lower upright portions projecting downwardly from the outer ends of said horizontal portions, and upper upright portions projecting upwardly from the inner ends of said horizontal portions, said lower upright portions being spaced laterally apart in the arc of a circle about and forming an upright enclosure for guiding said ball valve, said upper upright portions being spaced laterally apart in the arc of a circle about and forming an upright enclosure for guiding said loop, the lower ends of said lower upright portions being embedded in said gasket, a disc between and engaging notches in said upper upright portions adjacent their upper ends, said disc being in the upward path of and operable as an abutment for said eye to limit upward movement of said ball valve, and a holder for said wires having portions respectively receiving said horizontal portions and said upper upright portions, and having another portion receiving the lower end of said tubular guideway and holding the lower ends of said lower upright portions against displacement from said gasket.

2. The combination with a toilet tank, a water outlet fitting extending upwardly through the bottom of said tank and having an upwardly opening valve seat, an upstanding water overflow pipe connected to said fitting,

a vertically movable ball valve engageable with said seat and having an upright stem provided at its upper end with an eye, a bracket mounted upon said overflow pipe and having a horizontal arm provided with a vertically extending tubular portion receiving and forming a guideway for said stem, and actuating means for said ball valve including a pivotally mounted lifter lever, and a lifter link suspended from said lever and having a loop sleeved on said stem below said eye, of a guide structure for said ball valve and said stem operable to preclude any binding action between the loop and stem and between the stem and tubular guideway, comprising a series of wires having intermediate their ends spaced horizontal portions, lower upright portions projecting downwardly from the outer ends of said horizontal portions, and upper upright portions projecting upwardly from the inner ends of said horizontal portions, said lower upright portions being spaced laterally apart in the arc of a circle about and forming an upright enclosure for guiding said ball valve, said upper upright portions being spaced laterally apart in the arc of a circle about and forming an upright enclosure for guiding said loop, the lower ends of said lower upright portions being embedded in said gasket, and a holder for said wires having portions respectively receiving said horizontal portions and said upper upright portions, and having another portion receiving the lower end of said tubular guideway and holding the lower ends of said lower upright portions against displacement from said gasket.

3. The combination with a toilet tank, a water outlet fitting extending upwardly through the bottom of said tank and having an upwardly opening valve seat, a gasket on the bottom of said tank and surrounding said fitting, an upstanding water overflow pipe connected to said fitting, a vertically movable ball valve engageable with said seat and having an upright stem provided at its upper end with an eye, a bracket mounted upon said overflow pipe and having a horizontal arm provided with a vertically extending tubular portion receiving and forming a guideway for said stem, and actuating means for said ball valve including a pivotally mounted lifter lever, and a lifter link suspended from said lever and having a loop sleeved on said stem below said eye, of a guide structure for said ball valve and said stem operable to preclude any binding action between the loop and stem and between the stem and tubular guideway, comprising a series of wires having intermediate their ends spaced horizontal portions, lower upright portions projecting downwardly from the outer ends of said horizontal portions, and upper upright portions projecting upwardly from the inner ends of said horizontal portions, said lower upright portions being spaced laterally apart in the arc of a circle about and forming an upright enclosure for guiding said ball valve, said upper upright portions being spaced laterally apart in the arc of a circle about and forming an upright enclosure for guiding said loop, the lower ends of said lower upright portions being embedded in said gasket, and a holder for said wires having portions respectively receiving said horizontal portions and said upper upright portions.

4. The combination with a toilet tank, a water outlet fitting extending upwardly through the bottom of said tank and having an upwardly opening valve seat, an upstanding water overflow pipe connected to said fitting, a vertically movable ball valve engageable with said seat and having an upright stem provided at its upper end with an eye, a bracket mounted upon said overflow pipe and having a horizontal arm provided with a vertically extending tubular portion receiving and forming a guideway for said stem, and actuating means for said ball valve including a pivotally mounted lifter lever, and a lifter link suspended from said lever and having a loop sleeved

on said stem below said eye, of a guide structure for said ball valve and said stem operable to preclude any binding action between the loop and stem and between the stem and tubular guideway, comprising a series of wires having intermediate their ends spaced horizontal portions, lower upright portions projecting downwardly from the outer ends of said horizontal portions, and upper upright portions projecting upwardly from the inner ends of said horizontal portions, said lower upright portions being spaced laterally apart in the arc of a circle about and forming an upright enclosure for guiding said ball valve, said upper upright portions being spaced laterally apart in the arc of a circle about and forming an upright enclosure for guiding said loop, and a holding element for said wires having means for positioning said horizontal portions radially and said upper upright portions vertically, the central portion of said holding element being in engagement with the tubular portion of said bracket.

5. The combination with a toilet tank, a water outlet fitting extending upwardly through the bottom of said tank and having an upwardly opening valve seat, a gasket on the bottom of said tank and surrounding said fitting, an upstanding water overflow pipe connected to said fitting, a vertically movable ball valve engageable with said seat and having an upright stem provided at its upper end with an eye, a bracket mounted upon said overflow pipe and having a horizontal arm provided with a vertically extending tubular portion receiving and forming a guideway for said stem, and actuating means for said ball valve including a pivotally mounted lifter lever, and a lifter link suspended from said lever and having a loop sleeved on said stem below said eye, of a guide structure for said ball valve and said stem operable to preclude any binding action between the loop and stem and between the stem and tubular guideway, comprising a holder, wires projecting downwardly from said holder about and forming an upright enclosure for guiding said ball valve, wires projecting upwardly from said holder and forming an upright enclosure for guiding said loop, the lower ends of said downwardly projecting wires being embedded in said gasket, and a disc between and engaging notches in said upwardly projecting wires adjacent their upper ends, said disc being in the upward path of and operable as an abutment for said eye to limit upward movement of said ball valve, said holder having a portion engaging the lower end of said tubular guideway and holding the lower ends of said downwardly projecting wires against displacement from said gasket.

6. The combination with a toilet tank, a water outlet fitting extending upwardly through the bottom of said tank and having an upwardly opening valve seat, an upstanding water overflow pipe connected to said fitting, a vertically movable ball valve engageable with said seat and having an upright stem provided at its upper end with an eye, a bracket mounted upon said overflow pipe and having a horizontal arm provided with a vertically extending tubular portion receiving and forming a guideway for said stem, and actuating means for said ball valve including a pivotally mounted lifter lever, and a lifter link suspended from said lever and having a loop sleeved on said stem below said eye, of a guide structure for said ball valve and said stem operable to preclude any binding action between the loop and stem and between the stem and tubular guideway, comprising a holder, wires projecting downwardly from said holder about and forming an upright enclosure for guiding said ball valve, wires projecting upwardly from said holder and forming an upright enclosure for guiding said loop, and a disc between and engaging notches in said upwardly projecting wires adjacent their upper ends, said disc being in the upward path of and operable as an abutment for said eye to limit upward movement of said ball valve.

7. The combination with a toilet tank, a water outlet fitting extending upwardly through the bottom of said

tank and having an upwardly opening valve seat, a gasket on the bottom of said tank and surrounding said fitting, an upstanding water overflow pipe connected to said fitting, a vertically movable ball valve engageable with said seat and having an upright stem provided at its upper end with an eye, a bracket mounted upon said overflow pipe and having a horizontal arm provided with a vertically extending tubular portion receiving and forming a guideway for said stem, and actuating means for said ball valve including a pivotally mounted lifter lever, and a lifter link suspended from said lever and having a loop sleeved on said stem below said eye, of a guide structure for said ball valve and said stem operable to preclude any binding action between the loop and stem and between the stem and tubular guideway, comprising a holder, wires projecting downwardly from said holder about and forming an upright enclosure for guiding said ball valve, and wires projecting upwardly from said holder and forming an upright enclosure for guiding said loop, the lower ends of said downwardly projecting wires being embedded in said gasket, said holder having a portion engaging the lower end of said tubular guideway and holding the lower ends of said downwardly projecting wires against displacement from said gasket.

8. The combination of a toilet tank equipped with a water outlet fitting provided with an upwardly opening valve seat, an upstanding water overflow pipe connected to said fitting, a vertically movable ball valve engageable with said seat and having an upright stem provided at its upper end with an eye, a bracket mounted upon said overflow pipe and having a horizontal arm provided with a vertically extending tubular portion receiving and forming a guideway for said stem, and actuating means for said ball valve including a pivotally mounted lifter lever, and a lifter link suspended from said lever and having a loop sleeved on said stem below said eye, of a guide structure for said ball valve and said stem operable to preclude any binding action between the loop and stem and between the stem and tubular guideway, comprising a series of separate wires having intermediate their ends horizontal portions spaced laterally apart in a common horizontal plane, lower upright portions projecting downwardly from the outer ends of said horizontal portions, and upper upright portions projecting upwardly from the inner ends of said horizontal portions, said lower upright portions being spaced laterally apart in the arc of a circle about and forming an upright enclosure for guiding said ball valve, said upper upright portions being spaced laterally apart in the arc of a circle about and forming an upright enclosure for guiding said loop, a holder for said separate wires having two vertically spaced horizontal plates each having a plurality of holes therein, the holes in one of said plates being in vertical alignment with the holes in the other of said plates, said aligned holes cooperating to accommodate the upper upright portions of said wires, the lowermost of said plates having depending flange means provided with downwardly opening slots receiving the horizontal portions of said wires, the uppermost of said plates having a portion engageable with the lower end of said tubular guideway, and a disc between and engaging notches in the upper upright portions of said wires adjacent their upper ends, said disc being in the upward path of and operable as an abutment for the eye of the upright stem for said ball valve to limit upward movement of said ball valve.

9. The combination of a toilet tank equipped with a water outlet fitting provided with an upwardly opening valve seat, an upstanding water overflow pipe connected to said fitting, a vertically movable ball valve engageable with said seat and having an upright stem provided at its upper end with an eye, a bracket mounted upon said

overflow pipe and having a horizontal arm provided with a vertically extending tubular portion receiving and forming a guideway for said stem, and actuating means for said ball valve including a pivotally mounted lifter lever, and a lifter link suspended from said lever and having a loop sleeved on said stem below said eye, of a guide structure for said ball valve and said stem operable to preclude any binding action between the loop and stem and between the stem and tubular guideway, comprising a series of separate wires having intermediate their ends horizontal portions spaced laterally apart, lower upright portions projecting downwardly from the outer ends of said horizontal portions, and upper upright portions projecting upwardly from the inner ends of said horizontal portions, said lower upright portions being spaced laterally apart in the arc of a circle about and forming an upright enclosure for guiding said ball valve, said upper upright portions being spaced laterally apart in the arc of a circle about and forming an upright enclosure for guiding said loop, and a common holder for said separate wires having two vertically spaced horizontal plates each having a plurality of holes therein, the holes in one of said plates being in vertical alignment with the holes in the other of said plates, said aligned holes cooperating to accommodate the upper upright portions of said wires, the lowermost of said plates having depending flange means provided with downwardly opening slots receiving the horizontal portions of said wires, the uppermost of said plates having a portion engageable with the lower end of said tubular guideway.

10. The combination of a toilet tank equipped with a water outlet fitting provided with an upwardly opening valve seat, an upstanding water overflow pipe connected to said fitting, a vertically movable ball valve engageable with said seat and having an upright stem provided at its upper end with an eye, a bracket mounted upon said overflow pipe and having a horizontal arm provided with a vertically extending tubular portion receiving and forming a guideway for said stem, and actuating means for said ball valve including a pivotally mounted lifter lever, and a lifter link suspended from said lever and having a loop sleeved on said stem below said eye, of a guide structure for said ball valve and said stem operable to preclude any binding action between the loop and stem and between the stem and tubular guideway, comprising a series of separate wires having intermediate their ends horizontal portions spaced laterally apart, lower upright portions projecting downwardly from the outer ends of said horizontal portions, and upper upright portions projecting upwardly from the inner ends of said horizontal portions, said lower upright portions being spaced laterally apart in the arc of a circle about and forming an upright enclosure for guiding said ball valve, said upper upright portions being spaced laterally apart in the arc of a circle about and forming an upright enclosure for guiding said loop, and a common holder for said separate wires having means receiving the upper upright portions of said wires and having means receiving the horizontal portions of said wires, and means between and in engagement with the upper upright portions of said wires adjacent their upper ends in the upward path of and operable as an abutment for the eye of the upright stem of said ball valve to limit the upward movement of said ball valve.

enclosure for guiding said loop, and a common holder for said separate wires having two vertically spaced horizontal plates each having a plurality of holes therein, the holes in one of said plates being in vertical alignment with the holes in the other of said plates, said aligned holes cooperating to accommodate the upper upright portions of said wires, the lowermost of said plates having depending flange means provided with downwardly opening slots receiving the horizontal portions of said wires.

5 11. The combination of a toilet tank equipped with a water outlet fitting provided with an upwardly opening valve seat, an upstanding water overflow pipe connected to said fitting, a vertically movable ball valve engageable with said seat and having an upright stem provided at its upper end with an eye, a bracket mounted upon said overflow pipe and having a horizontal arm provided with a vertically extending tubular portion receiving and forming a guideway for said stem, and actuating means for said ball valve including a pivotally mounted lifter lever,

15 20 and a lifter link suspended from said lever and having a loop sleeved on said stem below said eye, of a guide structure for said ball valve and said stem operable to preclude any binding action between the loop and stem and between the stem and tubular guideway, comprising

25 25 a series of separate wires having intermediate their ends horizontal portions spaced laterally apart, lower upright portions projecting downwardly from the outer ends of said horizontal portions, and upper upright portions projecting upwardly from the inner ends of said horizontal portions, said lower upright portions being spaced laterally apart in the arc of a circle about and forming an upright enclosure for guiding said ball valve, said upper upright portions being spaced laterally apart in the arc of a circle about and forming an upright enclosure

30 35 for guiding said loop, and a common holder for said separate wires having means receiving the upper upright portions of said wires and having means receiving the horizontal portions of said wires, and means between and in engagement with the upper upright portions of

40 45 said wires adjacent their upper ends in the upward path of and operable as an abutment for the eye of the upright stem of said ball valve to limit the upward movement of said ball valve.
